United States Patent Office.

FRANK A. DESLOGE, OF ST. LOUIS, MISSOURI.

Letters Patent No. 91,095, dated June 8, 1869.

CLOTHES-MANGLE.

The Schedule referred to in these Letters Patent and making part of the same.

To all whom it may concern:

Be it known that I, FRANK A. DESLOGE, of St. Louis, in the county of St. Louis, and State of Missouri, have made certain new and useful Improvements in Clothes-Mangles; and I do hereby declare that the following is a full and clear description thereof, reference being had to the accompanying drawings, and to the letters of reference marked thereon.

The object of this invention is to form a smooth and, if needed, a yielding surface, which shall be properly heated, so that by the pressure from said surface upon clothes or similar stuffs, these shall be smoothed and ironed, as in the ordinary process of mangling.

To enable those herein skilled to make and use my said improvements, I will now more fully describe the same, referring to the accompanying

Figure 1 as a front elevation,

Figure 2 as a side elevation, and to

Figure 3 as a section of composite roller, used under circumstances hereinafter more fully explained.

In the ordinary uses of my said invention for ironing clothes, I support my said device upon any convenient table, A, by screwing the frame of the mangle to the plate B of said table.

My said mangle will consist principally of two or more rollers, C, which will usually be made of metal, such as cast-iron, having a polished outer surface.

Said rollers will be rotated upon hollow shafts, D, by sleeve-journals, F.

The journals F rest in proper bearings in a frame, G, supporting the said parts.

In order that the said rollers may permit the passage of clothes, one of the said journals F and its bearing-blocks will be arranged to slide up or down in the frame G, a rubber or other spring, K, and set-screw, H, regulating the pressure upon said journal, and thus also the pressure upon the cloth being passed under said roller.

Said rollers will be rotated by hand or other power, the journals F being arranged with gear-wheels, L, herefor.

In order that said rollers shall act upon the clothes not only by pressure, to smoothen the same, but also by the heat usual in operations of this character, I arrange the said hollow shafts D in connection with

reservoirs of heat, by means whereof heat may be transmitted within the rollers C.

In the usual arrangements which are practicable herefor, the shafts D will be arranged with perforations, E, and coal-gas, such as is used for purposes of illumination in cities, will be passed into said shafts D so that it issues from the perforations E. The streams of gas being ignited, will form so many flames, heating the roller C equitably as it revolves.

As combustion could not take place within the said rollers without an air-draught, I arrange the orifices c herefor.

In case illuminating-gas cannot be used, a spirit-lamp flame may be applied, or any other accessible source of heat.

In many cases, where clothing having hemmed or ridged edges, buttons or other projections, is to be mangled, I propose to use a yielding roller, C', in connection with the roller C. Said yielding roller will be formed of a wrapping of felting, compressed cotton, or other fibre, which will be tightly encased in a linen or other exterior wrapping, generally in the manner indicated in fig. 3. The material of such composite roller will allow the projections on clothes to pass between the rollers without undue strain, and the surface of the cloth, in such passage, in contact with the smoothing-roller C, will be properly mangled, and by reversing the stuff, to bring the reverse surface to contact with the roller C, the desired smoothness of both surfaces is achieved.

Having thus fully described my said invention,

What I claim, is—

1. The roller C, its orifices c, and sleeve-journals F, when combined with the shaft D and its perforations E, substantially as set forth.

2. The smoothing-roller C, when combined with the composite roller C', substantially as and for the purpose set forth.

In witness of said invention, I have hereto set my hand, in the presence of—

FRANK A. DESLOGE.
